UNITED STATES PATENT OFFICE

NORMAN L. SNOW, OF DETROIT, MICHIGAN, ASSIGNOR TO DIAMOND POWER SPECIALTY CORPORATION, OF DETROIT, MICHIGAN, A CORPORATION OF MICHIGAN

BOILER CLEANER

Application filed May 5, 1924. Serial No. 711,263.

This invention relates to boiler cleaners and among the objects of the invention are to provide an improved apparatus for cleaning boilers.

5 In the drawings which illustrate various embodiments of my invention:

Figure 1 is a vertical sectional view through one of the boiler cleaners;

10 Figure 2 is a sectional view of the construction shown in Figure 1 taken substantially on the line 2—2 of Figure 1;

Figure 3 is a side elevational view of a still further modification;

15 Figure 4 is a view on the line 4—4 of Figure 3;

Figure 5 is a cross section of the trigger taken along the line 5—5 of Figure 4; Figure 6 is a fragmentary plan view of the cam and trigger just before the cam drops off the 20 trigger to close the valve;

Figure 7 is a cross section on the line 7—7 of Figure 4;

Figure 8 is an end elevational view;

25 Figure 9 is a side elevational view showing a still further modification;

Figure 10 is an end elevational view;

Figure 11 is a top plan view showing a still further modification.

Describing first the particular embodiment 30 of my invention shown in Figures 1 and 2, 14 designates a rotary soot blower tube having discharge nozzles 15 through which jets of steam or suitable cleaning fluid are discharged to clean the surfaces of the boiler tubes 16 or other parts to be cleaned. Steam to the blower tube is supplied through a chamber 17 formed by the chamber casing 17a in which chamber is located a valve 18. The operation is as follows: The chain 19 is 35 pulled, rotating the blower tube 14 through the interengaging gears 29 and 28, the former of which is fixed to the chain sheave wheel shaft 29a and the latter to blower tube 14. This rotates the valve seat casing 20, the cover plate 21 and the valve 18. The cover plate 21 is secured to casing 20 by studs 22a, the plate being spaced from the casing by sleeves 22b. The valve 18 is carried by a pin 22 extending through the cover plate 21 to the valve seat casing 20. On continued rotation

projection 18a formed on the end of the valve which in the closed position extends into the recess 23 formed in the stationary chamber casing 17a strikes the side 25 of the recess and pushes the valve off the valve port 24 55 uncovering the opening straight through the cover plate 21 and the valve seat casing 20. The projection 18a on the end of the valve 18 which projection was formerly in the recess 23 then rides on the surface 26 of the 60 valve chamber maintaining the valve in the open swung position. In this position the valve is open and the blower pipe 14 is free to rotate until one of the stops 27 fastened to the gear wheel 28 comes into contact with the 65 pinion 29. In this position the valve is still open and in order to close the valve the pull on the chain 19 has to be reversed and the rotation of the element reversed, rotation continuing until the projecting end 18a of 70 the valve, which slightly projects beyond the cover plate 21, hits the top of the lug 20', continued rotation pushing it back into the recess 23 to swing the valve into the original 75 closed position.

As the valve mechanism above described is inclosed in a casing, there is nothing on the outside of the boiler to indicate the closed position, particularly as the blower pipe is often located high up on the boiler. Therefore, the operator might pull the chain and coming up against a hard point of operation, think he had reached the closed position of the valve. In order to avoid this objectionable feature I have provided a novel arrangement whereby the mechanism indicates definitely to the operator when the valve is closed. As shown in Figure 2, the operating chain 19 has a ball or enlargement 31. When the valve is in closed position the ball 31 will engage a hook 32 secured in some suitable position as to the boiler wall by means of the bolts 33. Therefore, the operator, by always bringing the ball back into engagement with the hook, will know that the complete operation of the blower pipe has taken place. While I have shown and described one mechanism for indicating when the valve is closed, it is obvious that various other mechanisms could be employed for this purpose 120

without departure from this feature of my invention.

Describing the constructions shown in Figures 3 to 7 inclusive 14 designates the blower pipe which is illustrated in all of the figures in all modifications similar to Figure 1. This blower pipe is rotated by means of the chain 66 in the manner previously described in connection with the other constructions, which 10 chain extends over a sheave wheel 67 which drives a gear wheel 68 that carries a cam 69.

This cam 69 is made with a raised portion 77 adjacent one end thereof as shown in Figure 7. As shown in Figures 3 and 4, this 15 raised portion 77 engages the face 70a of trigger 70 after the valve has been fully opened and at the beginning of the blowing cycle of the unit. In opening the valve, the face 71 of the trigger contacts with the downwardly facing edge 75 of the cam 69 pushing the trigger outwardly and depressing the valve stem 90 to open the valve 72. This construction is in accordance with the structure shown in various copending applications of 20 this inventor, the novelty of the present construction consisting principally in the provision of a cam and cooperating trigger construction, which when the valve is opened, will permit the trigger to snap off of the cam 25 suddenly, causing the valve to close practically instantaneously. After the trigger 70 has passed over the raised surface 77 of the cam, it rides down onto the lower surface 73 where it continues to ride in a normal 30 manner until the element is reversed and the trigger on its return trip contacts with this raised portion 77. The trigger, as indicated 35 in Figure 5 and also in Figure 3, is formed with a depressed portion 74 which, as shown 40 in dotted lines in Figure 4, is tapered gradually to meet the lower part of face 71. On the return trip of the trigger, the edge of this tapered portion 74 contacts with the corner 45 77a of the raised surface of the cam, causing the trigger to swing outwardly to the left in Figure 3. This causes the portion 71 of the trigger, namely, the high portion, to ride entirely off of the surface of cam 69, the tapered portion 74 of the trigger now riding on the 50 portion 73 of the cam. The position of the parts is shown in Figure 6 just before the trigger is ready to snap off of the cam.

As pointed out in discussing the valve opening, the face 75 of the cam rides up the 55 broad face 71 of the trigger causing the valve to open gradually. The reverse effect now takes place, inasmuch as this broad face 71 has been pushed off the cam and the tapered 60 face 74 of the trigger coming to a point is permitted to snap rapidly off of the portion 73 of the cam. In order to normally yieldingly hold the trigger to the right in Figure 3, and to permit it to swing to the left when the valve starts to close in the manner above 65 described, I have provided a compression

spring 79, mounted between the head 79h of bolt 79a and the bearing bracket 79b and surrounding the bolt 79a. This bolt is axially slidable, against the compression on the spring, in the fixed bracket bearing 79b and is provided with a head 79c bearing against trigger 70 to yieldingly hold the trigger against bracket 79b, thus normally holding the trigger 70 toward the right as shown in Figure 3. Trigger 70 has a pivotal bearing 75 on bolt 79a permitting the trigger to swing toward the left during the valve closing, by reason of an opening 79d, somewhat larger than the bolt 79a and preferably oppositely flaring to readily permit the trigger end to move to the left as shown in Figure 3. During the swinging of the trigger 70 to the left as shown in Figure 3, continuous contact of the trigger and valve stem 90 is maintained by reason of a projection 79f formed upon 80 the trigger.

Stop mechanism is provided to prevent the valve from closing until a predetermined number of oscillations are completed. This stop mechanism is essentially the same as that shown in Figures 9 and 9a of my co-pending application, Serial Number 663,002. In the particular case shown, the mechanism is set so that six cycles must be completed. For this purpose the disk 80 is fastened to the face of the gear wheel 68. 81 is a toothed wheel rotatably mounted on the side of the disk 80 as by a stub shaft 81a and this wheel is urged against the side of the disc by a spring 81y; six of the spaces 81a between the teeth of the wheel 81 are relatively deep while one of the spaces 86 is quite shallow. Pawl 83 is mounted to swing on the sheave wheel shaft 83a. The nose of this pawl may be so shaped with relation to the sides of notches 81a as to permit the pawl to ride freely over the notches in one direction of travel of the blower tube 14, while causing the notched wheel to travel ahead one notch by reason of engagement of pawl 83 with the point of the notch in the opposite direction of travel of the blower tube 14. A notch is cut in the disk 80 at 82 and when the pawl 83 drops into this notch 82 further rotation in a counter-clockwise direction is prevented. In this position of the parts shown the blower pipe 14 cannot be turned counter-clockwise, that is, the valve 72 cannot seat. The blower is then turned in a clockwise direction until a stop 84 presses against the bracket 85. Counter-clockwise rotation will then bring the toothed disk 81 under the pawl 83, and when the latter ultimately rides in the space 86 it allows the pawl 83 to ride over the notch 82 in the disk 80 and the valve 72 may then close. Means is thus provided to keep the valve from closing throughout a predetermined number of oscillatory cycles. A ball 87 on the operating chain 66 will then have been pulled under the fork 88 (similar to that shown in Figs. 1 and 120 125 130

2) on the side of the boiler so that the operator knows the valve 72 is closed and the blowing has been completed. In starting the next blowing operation the ball 87 is unhooked from the fork 88 and the valve is opened by turning the blower pipe 14 in a clockwise direction. The oscillations are continued in each direction to the limit of movement until the toothed disk 81 is in the 10 position shown in Figure 4. The operation from this point is then as above described. The stop 84 may be set in any one of the holes 89 provided in the disk so as to limit the oscillations to the desired blowing arc for the 15 blower pipe. Another feature of the invention shown particularly in Figure 4 is the labyrinth packing arrangement around the valve stem. This provides a means for sealing the stem without the use of any soft packing 20 around the valve stem. In the particular illustration of this feature of the invention shown in the drawings the stem 90 of the valve 72 fits closely inside the casing 91 and a series of grooves 92 are cut out and spaced 25 apart in this casing.

Describing now the constructions shown in Figs. 8 and 9, which illustrate a modification of the type of mechanism shown in Figs. 1 and 2, the blower pipe 14 is similar 30 in this construction to that shown in the previous described constructions. It is, however, driven by a bevel gear 107 through a bevel pinion 108, rod 109 and handwheel 110. 35 111 is the main body of the blower head which contains the slide valve 112, shown in the closed position in Fig. 15. The rod 109 has a threaded portion 113 on which there is mounted a nut 114. This nut 114 moves up 40 and down on the threaded portion 113 of the rod 109 between the limits allowed by the fixedly mounted member 115 which has projecting lugs 116 and 117 which indicate the open position and the closed position of the controlling valve in the blower unit. The 45 nut 114 is prevented from turning because of its flat side 118 engaging against the flat side of the member 115. In the position shown in Fig. 8 the handwheel 110 has been turned to the limit to rotate the blower pipe 50 in a clockwise direction and the nut 118 has been brought up against the stop 117 giving indication that the valve has been closed.

Describing now in detail the construction shown in Figs. 10 and 11, the blower pipe 14 in this construction is actuated by means of a ratchet device, the slide valve being similar 55 to that shown in connection with Figs. 8 and 9. For operating the blower unit, chains 119 and 119' are alternately pulled, giving 60 a rocking motion to the cradle 120. This cradle carries the reversible pawl 121 adapted to engage the ratchet wheel 122 with which it may be retained in resilient contact in any suitable manner. In the position shown 65 of pawl 121 the ratchet wheel 122 will be

turned in a clockwise direction when the chains are actuated. The motion of the cradle 120 is limited by pins 123 and 124 striking the projections 125 and 125' fastened to the main casing. When the lug 126 fastened to the ratchet 122 has made almost a complete revolution it will strike against the gear sector 129 carried by the cradle 120, causing this gear sector to swing and thus to move the pawl 121 so that the other end of 70 this pawl will engage the ratchet 122. Further operation of the cradle 120 will move the ratchet wheel 122 in the opposite direction. Ordinarily, the position of the ball 130 on the chain 119 will operate between the upper and lower positions marked "upper position" and "low position" in Fig. 10. The low position is determined by the pin 124 striking the projection 125'. The pin 124 is fastened to a sliding member 131 and in turn 80 this sliding member 131 is manipulated by a pin 132 working in a groove 133 in the ratchet wheel 122. This groove 133 is concentric except for one end which moves outwardly from the center as shown in Fig. 10. When 85 the pin 132 is working in the concentric position of the groove 133 the sliding member 131 and the pin 124 will be drawn in somewhat from the position shown in Fig. 11, so that the pin 124 will strike the stop or 90 projection 125' limiting the motion of the cradle 120 so that the ball 130 can only move downward to the low position. When, however, the ratchet wheel 122 is rotated in a counter-clockwise direction to the position 95 shown in the drawings and where the valve to the blower pipe 14 will be closed, the pin 132 with the sliding member 131 and the pin 124 will be moved to the outward position shown in Fig. 10 and the pin 124 when 100 the chain 119 is pulled will miss the projection 125' and the ball 130 will then drop to a position under the hook 135 giving indication that the valve to the blower unit 14 is 105 closed.

What I claim as my invention is:

1. In a boiler cleaner, the combination with a rotatable blower pipe adapted to discharge jets of cleaning fluid, of a valve for controlling the supply of said cleaning fluid to said pipe, means operable to actuate the said valve upon the rotation of the blower pipe, and means for rotating said pipe including a member fixed to rotate with the blower pipe, and a flexible operating member engageable 115 with the first said member, and stationary indicating means cooperating with said flexible member for indicating when the valve is in a position to shut off the supply of 120 cleaning fluid.

2. In a boiler cleaner, the combination with a rotatable blower pipe adapted to discharge jets of cleaning fluid, of a valve for controlling the supply of said cleaning fluid to 125 said pipe, means operable to actuate the valve

upon rotation of the blower pipe, and means for rotating said pipe, including a sheave and a chain operably engaging the sheave, and a stationary member located adjacent the path of the chain and cooperating with a predetermined portion thereof for indicating when the valve is in a position to shut off the supply of cleaning fluid to said pipe.

3. The combination with a rotatable blower pipe and a valve movable relative to said pipe and operable upon rotation of the pipe to control the flow of cleaning fluid to said pipe, of means for visually indicating when the valve is in closed position, said means including a stationary member and a member movable rectilinearly of the said stationary member upon rotation of the blower pipe.

In testimony whereof I affix my signature.

20 NORMAN L. SNOW.
